(57) **CLAIM**

The ornamental design for computerized tomography scanner, as shown and described.

DESCRIPTION

1. Computerized tomography scanner

1.1 is a perspective view showing the computerized tomography scanner of our design;

1.2 is a front elevational view thereof;

1.3 is a rear elevational view thereof;

1.4 is a left side elevational view thereof;

1.5 is a right side elevational view thereof;

1.6 is a top plan view thereof; and

1.7 is a bottom plan view thereof.

The portions of the computerized tomography scanner shown with YELLOW highlighting form no part of the claimed design.
